UNITED STATES PATENT OFFICE.

FREDERICK S. PINKHAM, OF EVERETT, MASSACHUSETTS.

DESIGN FOR AN ARM-BADGE.

SPECIFICATION forming part of Design No. 22,261, dated March 7, 1893.

Application filed January 11, 1893. Serial No. 458,093. Term of patent 14 years.

To all whom it may concern:

Be it known that I, FREDERICK S. PINKHAM, a citizen of the United States, residing at Everett, in the county of Middlesex and 5 State of Massachusetts, have invented and produced a new and original Design for a badge, of which the following is a specification, reference being made to the accompanying drawing, forming a part thereof.

10 The drawing shows a face view of my newly designed badge.

My design consists in a fluted fan shaped head *a*, from the lower end of which drapery *b*, hangs in plaits or folds, the lower end of 15 said drapery being finished with ornamental fringe *c*. A rosette *d*, is supported at the

base of the fan shaped head *a*, at the junction of the head *a*, and drapery *b*, and from said rosette narrow strips of ribbon hang, terminating at or about the junction of the 20 fringe and drapery, exposing said fringe.

I claim—

The design for a badge, herein shown and described.

In testimony whereof I have signed my 25 name to this specification in the presence of two subscribing witnesses.

FREDERICK S. PINKHAM.

Witnesses:

BERNICE J. NOYES,
CHARLES B. CROCKER.
